UNITED STATES PATENT OFFICE.

JAMES C. PARMERLEE AND ALONZO SWIFT, OF SEDALIA, MISSOURI.

DEVICE FOR CONNECTING STRAPS WITH RINGS, &c.

SPECIFICATION forming part of Letters Patent No. 310,719, dated January 13, 1885.

Application filed June 16, 1884. (No model.)

To all whom it may concern:

Be it known that we, JAMES C. PARMERLEE and ALONZO SWIFT, citizens of the United States, residing at Sedalia, Missouri, have invented new and useful Improvements in Devices for Connecting Straps with Rings and other parts of Harness, of which the following is a specification.

This invention has for its object to provide novel and efficient means for securing the overlying parts of strap-loops for connecting the strap with a ring, buckle, or similar contrivance, as in halters, reins, bridles, and other parts of harness, whereby we avoid sewing or riveting the strap, and enable the ring, buckle, or other device to be attached or detached with facility and convenience. This we accomplish in the manner and by the means hereinafter described and claimed, reference being had to the accompanying drawings, illustrating our invention, in which—

Figure 1 is a perspective view of a strap connected with a ring in accordance with our invention; Fig. 2, a longitudinal sectional view of the same; Fig. 3, a transverse sectional view through the box-loop on the line *y y* of Fig. 2, and Fig. 4 detached perspective views of the box-loop and the tongue-bar.

Referring to the drawings, the number 1 indicates a strap bent around at one end to form a loop containing the ring 2, the turned extremity 3 of the strap overlying the strap-body. A metallic box-loop, 4, of rectilinear form, encircles the two parts of the strap, and is composed of top and bottom walls and end walls 5, each of the latter having on its inner side a groove, 6, located at or near a point centrally between the top and bottom walls, and the inner side of the bottom wall is constructed with a rectilinear recess, 7, at one edge, to produce the transverse shoulder or abutment 8. A straight flat bar, 9, is provided with tongues 10, to enter holes 11 in the turned extremity 3 of the strap, said bar being inserted between the body of the strap and the turned extremity thereof, so that its ends pass into the grooves 6, and its tongues 10 pass through the holes in the strap, and their points fall behind the shoulder or abut-

ment 8, which sustains the points of the 50 tongues against the pressure exerted on them by longitudinal strains on the strap. The tongue-bar, being interposed between the two overlying parts of the strap will thereby be held from loss or displacement, and the movement of the tongue-bar into the box-loop is limited by its ends coming against the inner terminations of the grooves.

To detach the parts, it is simply necessary to push the strap-body slightly through the 60 box-loop toward the ring, and then draw the turned extremity of the strap outward sufficiently to permit the tongue-bar to be conveniently removed, when the several parts may be disconnected.

The invention is useful for connecting straps with any part of a harness—such as halters, reins, buckles, and the like—and by the construction described and shown it is not necessary to sew or rivet the strap.

We do not confine ourselves to providing a tongue or tongues on the bar, as such may be dispensed with, as the wedging action of the bar on the two parts of the strap will sometimes be sufficient to securely confine all in 75 proper position; but a tongue or tongues on the bar are desirable in that a much stronger and more substantial attachment of the parts is thereby provided.

Having thus described our invention, what 80 we claim is—

1. The combination of the box-loop having top and bottom walls, and end walls having grooves in their inner sides, with the bar having its ends adapted to the grooves, substantially as described.

2. The combination of the box-loop having top and bottom walls, and end walls having grooves in their inner sides, with the bar having its ends adapted to the grooves, and provided intermediate its ends with a tongue, substantially as described.

3. The combination of the box-loop having its bottom wall constructed with the transverse shoulder or abutment, and its end walls 95 constructed with the grooves intermediate the top and bottom walls, with the bar having its ends adapted to the grooves, and provided in-

termidate its ends with tongues the points of which are adapted to bear against the shoulder or abutment, substantially as described.

4. The combination, with a ring and a strap having the turned extremity lying against the body of the strap, and provided with holes, of the box-loop having grooves in its end walls, and the tongue-bar interposed between the strap-body and the turned extremity with its

tongues entering the holes therein, substantially as described.

In testimony whereof we affix our signatures in presence of two witnesses.

JAMES C. PARMERLEE.
ALONZO SWIFT.
